UNITED STATES PATENT OFFICE.

WILBUR E. HARRIMAN, OF NORTH CHATHAM, NEW HAMPSHIRE.

DESIGN FOR A HANDLE SOCKET-PIECE FOR HAND-SCRAPERS.

SPECIFICATION forming part of Design No. 28,568, dated May 10, 1898.

Application filed March 30, 1898. Serial No. 675,806. Term of patent 7 years.

To all whom it may concern:

Be it known that I, WILBUR E. HARRIMAN, a citizen of the United States, residing at North Chatham, in the county of Carroll and 5 State of New Hampshire, have invented a new and original Design for a Handle Socket-Piece for Hand-Scrapers, of which the following is a specification.

This invention relates to a new and original 10 design for a handle socket-piece for hand-scrapers; and it has for its object to provide a design of this character that shall be both useful and ornamental.

The leading feature of the design resides 15 in an elongated body having a tubular socket portion tapering into a contracted cylindrical neck intermediate the ends of the body and a conico-elliptic foot portion at the end opposite the socket portion, said foot portion being 20 provided at its widest end or base with a continuous flat annular flange projecting outwardly in a plane at right angles to the length of the body, the complete flange at the base of said foot portion being of a diamond shape.

25 A minor feature of the design resides in having the diamond-shaped flange at the base of said foot portion provided with rounded corners.

In the drawings, Figure 1 is a perspective view of a handle socket-piece for hand-scrapers embodying the herein-described design. Fig. 2 is a cross-sectional view thereof 30 on the line 2 2 of Fig. 1.

Referring to the accompanying drawings, the numeral 1 designates an elongated body 35 provided with a cylindrical tubular socket portion 2. The tubular socket portion 2 tapers from one end of the body into a contracted cylindrical neck 3, which is located intermediate the ends of the body, and from 40 the neck 3 the said body is flared at the end opposite the socket portion 2 into a conico-elliptic foot portion 4. The conico-elliptic foot portion 4 by reason of its elliptical form is necessarily of a greater width in one direction than in the other, and at its base or 45 widest end the said conico-elliptic portion is provided with a continuous flat annular flange 5. The flange 5 projects outwardly from the foot portion and is disposed in a 50 plane at right angles to the length of the body, the complete flange 5 being in the form of a diamond figure and having rounded corners 6.

What I claim is—

55 The design for a handle socket-piece for hand-scrapers, herein shown and described.

In testimony that I claim the foregoing as my own I have hereto affixed my signature in the presence of two witnesses.

WILBUR E. HARRIMAN.
